UNITED STATES PATENT OFFICE.

HENRIK AUGUST BERTHEAU, OF STOCKHOLM, SWEDEN.

FOUR-STROKE PETROLEUM-MOTOR.

SPECIFICATION forming part of Letters Patent No. 700,295, dated May 20, 1902.

Application filed April 3, 1901. Serial No. 54,202. (No model.)

To all whom it may concern:

Be it known that I, HENRIK AUGUST BERTHEAU, a subject of the King of Sweden and Norway, residing at Stockholm, Sweden, have 5 invented certain new and useful Improvements in Four-Stroke Petroleum-Motors; and I do hereby declare the following to be a full, clear, and exact description of the invention, such as will enable others skilled in the art 10 to which it appertains to make and use the same, reference being had to the accompanying drawings, and to figures of reference marked thereon, which form a part of this specification.

15 This invention relates to improvements in petroleum-engines, and especially to starting and reversing mechanism and means for changing speed, and has for its object to provide means for stopping and starting explosive engines that use compressed burned gases, to start the engine on a two-stroke cycle by the aid of such compressed gases and then change to a four-stroke cycle, simultaneously cutting off the supply of compressed 20 burned gas and admitting an explosive mixture, to operate the engine either direct or reverse on either two or four stroke cycle and control it by a single shiftable cam-sleeve. Means are also provided to control the rapid- 25 30 ity of combustion of the explosive mixture, as will be particularly pointed out in the following description.

Referring to the drawings, in which like parts are similarly designated, and in which 35 is shown a single-cylinder engine to which the invention is applied, Figure 1 is a side elevation, a part being in section, taken on line A B, Fig. 3; Fig. 2, a partial horizontal longitudinal section; Fig. 3, an end view, partly 40 in section; Fig. 4, a section on the line C D of Fig. 2; Fig. 5, a top plan view showing in dotted lines the means for shifting the cams; and Fig. 6 is a section taken on line E F, Fig. 3.

45 1 is the cylinder; 2, the piston therein, connected by connecting-rod 3 to a suitable crank on the main shaft 4 of the engine, which shaft carries one or two, as may be desired, fly-wheels 19, capable of acting as belt-wheels 50 also.

The cylinder 1 is provided with a suitable casing 5, between which and the cylinder is

the usual space 5^a for the circulation of a cooling liquid. The cylinder-head, preferably formed hollow, as at 6, for the reception 55 of a cooling liquid, contains the several ports, the valves that control them, and the vaporizer. This vaporizer (shown in Figs. 1, 2, and 4 in section) comprises a body portion 9, provided with a tortuous channel and containing 60 a spring-loaded hot-air-inlet valve 23, which at the same time controls the inlet 22 from the hydrocarbon-reservoir. (Not shown.) When the valve 23 is opened by suction created by the piston, hot air and liquid hydrocarbon are simultaneously drawn in, and the 65 vapor generated from contact with the hot sides of the vaporizer 9 will pass through the passages 24, 24^a, 24^b, and 24^c to the spring-held inlet-valve 20, where it enters the annular chamber 27 to be mixed with the air entering through the openings 21 above valve 20. The hot air that mixes with the liquid hydrocarbon enters through openings 25 in the outer wall of the chimney 28, passes through 70 the tortuous passage 26, formed in the annular space between the inner and outer wall of the chimney by means of semicircular flanges 26^a, formed on the inner wall of the chimney, and then goes through the passage 75 28^a to the valve 23.

The vaporizer is heated by a suitable lamp placed below it and which also heats the igniter-tube 29, that enters the inlet-passage 8 just below the inlet-valve 20. Means are provided for additionally loading the inlet-valve 20 by increasing the tension of its loading-spring 44 to decrease the time that it remains open, and this consists of a bent lever 45, pivoted at 45^a, one end of which takes under 85 the spring 44, and the other end is engaged by a reciprocable collar 46 and is independent of the cam-shaft. The means for operating this collar will be described later. Air is drawn in through the passages 21 in the inlet-valve 90 casing and meets the hydrocarbon vapor from the vaporizer and is well mixed on entering the cylinder. During normal running means are provided for storing a portion of the products of combustion in a suitable reservoir 13^a. 95 The force of the explosion will be communicated through the passage 10, Fig. 6, to open the spring-held valve 12, located between said passage 10 and one, 13, through the cyl- 100

inder-head, that leads to the reservoir 13^a, where the gases are stored under pressure to be used for starting the engine.

The regulation and proper control of the several valves is done by a cam-sleeve 15, shiftable axially on a shaft 14, journaled in suitable brackets 14^a and driven by chain or belt wheel 16, which is itself driven at half-speed from the crank-shaft 4 by means of the wheel 17 and a sprocket-chain or a belt 18.

The cam-sleeve 15 is provided with sets of cams (indicated as I, II, III, IV, and V) and is connected at one end to a shifting arm 34, forming part of a rack 34^a, shiftable in a direction parallel to the axis of the cam-sleeve. To effect the shifting of the rack 34^a, there is geared with it a sector rack or pinion 35, secured to the hollow shaft 36 of the controlling device. This shaft 36 has secured to it a suitable head 38, in which is pivoted at 43 a hand-lever 37. This hand-lever has pivoted to it intermediate its ends at 37^a one end of a link 47^a, whose other end is pivoted to one end of the sleeve 47, slideable in the hollow shaft 36, said shaft being provided with oppositely-situated longitudinal slots 36^a at a suitable point. A suitable bolt 47^b passes through the sleeve 47, the slots 36^a, and the collar 46, thus securing said collar to the sleeve and allowing it to be moved on the shaft 36 within the limit of motion allowed by said slots.

A spring 40 is secured at one end to the head 43 and rotatable with it and the shaft 36. The free end of this spring carries a pawl 39, adapted to take into notches on a sector or plate 42, secured to or forming part of the head 41 of the regulating device. Near the free end of the spring 40 is secured a finger-grip pawl 48, secured to the hand-lever 37. The described arrangement permits the lever 37 to be positioned along the rack 48^a, thereby moving the sleeve 47 and its connected collar 46 to depress the end of the lever 45, whose nose takes under the spring 44 on the inlet-valve to increase the tension of this spring.

By depressing the hand-lever 37 without releasing the pawl 48 from the rack 48^a the spring 40 is bent downward sufficiently to disengage the tooth 39 from the sector 42 to permit the rotation of the shaft 36 and the pinion 35, secured to the lower end of it, to shift the cam-roller 15 on the axle 14. The described arrangement permits the hand-lever to be moved around a vertical axis and to be moved vertically around a horizontal axis.

The starting and control of the engine are effected by suitably positioning the cam-sleeve 15 to operate the exhaust and the pressure-gas valve or only the former.

The cam I is that which when positioned under the roller 31^a on the lever 31, that opens the exhaust-valve, will hold the valve open, the piston being subjected to atmospheric pressure during its travel, and thus

prevented from drawing in a charge. The engine will consequently be stopped. To the side of this cam are two others, II and III, the cams that open the exhaust-valve at every fourth stroke for direct and reverse running with a four-stroke cycle, and to the side of these cams are those, IV and V, to open the pressure-gas valve 12 and the exhaust-valve at every other stroke for direct or reverse running—that is, at every revolution of the motor—whereby the motor is run on two-stroke cycle.

It will be observed that the throw of the two-stroke-cycle cams IV and V is larger than that of the four-stroke-cycle cams II and III, and the object of this is for the latter cams to be out of range of the roller 33^a on the lever 33, that opens the pressure-gas valve 12, so that the exhaust-valve only will be operated, the ends of the levers 33 and 31 being in the same plane. Consequently the exhaust-valve will be depressed more than is absolutely necessary when the engine is working on a two-stroke cycle by the difference between the throw of the cams for two and four stroke cycle.

The operation is as follows: Supposing the storage-reservoir 13^a to be full of gas, the hand-lever 37 is depressed to bring the pawl 39 out of its notch and then swung horizontally to the starting position indicated on the plate 42 to move either the cam IV or V into position to contact with the rollers 31^a and 33^a. This plate has only three notches corresponding to the position of rest and of direct and reverse running on four-stroke cycle. The position for starting is only indicated, as the two-stroke cycle is only necessary for a few revolutions to enable the fly-wheel to attain sufficient inertia to draw in the charge.

After these few strokes the lever is revolved to snap the pawl 39 into one of the notches indicating direct or reverse running. At starting the piston is supposed to be at about half-stroke and pressure-gas is admitted through valve 12 and passage 10 to move the piston 2, and when this has about reached the end of its stroke the pressure-gas valve is closed and the exhaust-valve 30 is opened to allow the piston to expel the expanded gas. The piston then returns, the exhaust-valve is closed, and the pressure-gas valve again opened until the engine has made a few revolutions, when the hand-lever is rotated to snap the pawl into a four-stroke-cycle notch, the sleeve 15 being correspondingly and simultaneously shifted. The pressure-gas valve is thus idle, because the cam operating the exhaust-valve has not enough throw to reach the roller on the end of the lever 33, that actuates this valve. The cams II and III being suitably positioned, the motion of the piston 2 from left to right, Fig. 1, will create a vacuum sufficient to open the valve 20 and the suction of which will be communicated through the vaporizer to the valve 23

to open it to admit a new charge of liquid hydrocarbon and a small amount of air through the passage 28^a, that has been previously heated in the annular space 26 of the chimney 28. The charge being drawn in on one stroke, compression will take place on the next and ignition and explosion on the third, the exhaust-valve then opening to exhaust the products of combustion. Some of these products of combustion on the explosion-stroke will have passed through the passage 10 and pressure-gas valve 12 into the storage-reservoir for future use. To stop the motor, the cam I is moved under the end of the lever actuating the exhaust-valve to hold this valve open. Consequently no vacuum can be created to open the inlet-valve and draw in the charge, nor can air or gas be compressed. In order to regulate the speed of the motor, the hand-lever 37 is positioned on the rack 48^a to move the collar 46 to increase the tension of the coil-spring 44 on the inlet-valve. This retards the opening of this valve, and consequently the quantity of gas mixture is reduced. When the speed of the engine is reduced, it is of course necessary to retard the ignition of the charge correspondingly, so that there will be no counter-pressure on the piston. This retardation can be partially accomplished by reducing the volume of explosive mixture admitted; but the amount of retardation is not sufficient, and it is necessary to produce an additional retardation, and this is accomplished by increasing the quantity of hydrocarbon to make a gas mixture richer in hydrocarbon simultaneous with the change of volume. This result is automatically accomplished by simply increasing the tension of the inlet-valve spring. This will cause a greater proportional quantity of hydrocarbon to be drawn into the cylinder, as the tension of the spring on the valve 23, controlling the inlet of liquid hydrocarbon, is not varied. The reason of this is that the entering air at valve 23 has an injector effect on the hydrocarbon admitted through 22. Throttling the inlet-valve will decrease the extent of opening of said valve and likewise decrease the lift of valve 23. A decrease of the lift of this valve 23 will cause a smaller volume of air of annular shape to draw in the hydrocarbon; but when the lift of this valve 23 is greater the thickness of the annulus of air admitted is also greater and its speed is less. Therefore there is a greater quantity of air having less injecting force acting to draw in the hydrocarbon.

Having thus described my invention, what I claim as new therein, and desire to secure by Letters Patent, is—

1. In a hydrocarbon-motor, in combination, inlet and exhaust valves, a device to control each of said valves, axially-shiftable cams to operate said devices and means to retard the action of the inlet-valve, to automatically increase the quantity of hydrocarbon vapor to

form an explosive mixture richer in hydrocarbon, substantially as described.

2. In a hydrocarbon-motor, in combination, inlet and exhaust valves, a device to control each of said valves, axially-shiftable cams to operate said devices, means to simultaneously admit air and hydrocarbon, and means to throttle the inlet-valve and thereby automatically control the means for the admission of air and hydrocarbon, substantially as described.

3. In a hydrocarbon-motor, in combination, inlet and exhaust valves, a lever acting on each valve, axially-shiftable cams operating said levers and means to shift the cams, a vaporizer external to the engine and communicating with the inlet-valve, means operated from the cam-shifting means to additionally load the inlet-valve and an auxiliary valve to admit both air and hydrocarbon to the vaporizer, automatically operated by the degree of vacuum and controlled by the inlet-valve to automatically proportion the air and hydrocarbon, substantially as described.

4. In a hydrocarbon-engine, in combination, inlet and exhaust valves, levers controlling them, a driven cam-shaft axially shiftable, cams thereon shiftable under the levers controlling the exhaust-valve, whereby said valve can be held open, opened at every other stroke and opened at every fourth stroke and means to vary the load on the inlet-valve.

5. In a hydrocarbon-engine, in combination, an inlet and an exhaust valve, and a valve controlling gas under pressure, levers controlling them, a driven cam-shaft axially shiftable, cams thereon to actuate the inlet, exhaust and pressure-gas valves, and hand-operated means to additionally load the inlet-valve and shift the cam-shaft at will, substantially as described.

6. In a hydrocarbon-engine, in combination, an air-inlet and an air-exhaust valve, and one controlling gas under pressure, a vaporizer external of the engine and arranged to deliver combustible through the inlet-valve simultaneously with air, a valve in the vaporizer controlling the simultaneous inlet of hot air and liquid hydrocarbon and operated by suction, a driven cam-shaft axially movable, means for varying the load on the inlet-valve and for shifting the cam-shaft to cause the engine to operate on a two or four stroke cycle, or to maintain the exhaust-valve open, substantially as described.

7. In a hydrocarbon-engine, in combination, a spring-held air-inlet valve and an exhaust-valve, and one controlling gas under pressure, a vaporizer external of the engine and arranged to deliver combustible through the inlet-valve simultaneously with air, a valve in the vaporizer controlling the simultaneous inlet of hot air and liquid hydrocarbon, and operated by suction, a driven cam-shaft axially movable, a rack connected to said shaft, a pinion in gear therewith, a hol-

low shaft secured to the pinion, a hand-lever arranged to rotate the shaft, a collar on the shaft operated by the hand-lever, and a lever pivoted to take under said collar and additionally load said valve when the collar is depressed, substantially as described.

5 In testimony that I claim the foregoing as

my invention I have signed my name in presence of two subscribing witnesses.

HENRIK AUGUST BERTHEAU.
